US00D529629S

(12) **United States Design Patent** (10) Patent No.: **US D529,629 S**
Zarb (45) Date of Patent: ** Oct. 3, 2006

(54) **TRIM SYSTEMS COMPONENT FOR
BUILDING STRUCTURES**

(75) Inventor: **Joseph Emmanuel Zarb**, Bonnyrigg Heights (AU)

(73) Assignee: **James Hardie International Finance B.V.**, Amsterdam (NL)

(**) Term: **14 Years**

(21) Appl. No.: **29/219,596**

(22) Filed: **Dec. 17, 2004**

(30) **Foreign Application Priority Data**

Jun. 17, 2004 (AU) 13005/2004

(51) **LOC (8) Cl.** **25-01**

(52) **U.S. Cl.** **D25/119**

(58) **Field of Classification Search** D25/119, D25/61, 136; 52/716.1, 290, 287.1, 288.1

See application file for complete search history.

(57) **CLAIM**

The ornamental design for a trim systems component for building structures, as shown and described.

DESCRIPTION

FIG. 1 is a perspective view of the trim systems component for building structures of the present design;

FIG. 2 is a front view thereof;

FIG. 3 is a right side view thereof;

FIG. 4 is a left side view thereof; and,

FIG. 5 is a top view thereof.

The bottom view of the trim systems component for building structures is the same as the top view.

The trim systems component for building structures has been broken on the end indicating indefinite length.
